No. 834,049.

PATENTED OCT. 23, 1906.

C. J. DUNCAN.
ROTARY ENGINE.
APPLICATION FILED MAR. 3, 1906.

UNITED STATES PATENT OFFICE.

CLARK J. DUNCAN, OF WINDBER, PENNSYLVANIA.

ROTARY ENGINE.

No. 834,049.

Specification of Letters Patent.

Patented Oct. 23, 1906.

Application filed March 8, 1906. Serial No. 304,109.

To all whom it may concern:

Be it known that I, CLARK J. DUNCAN, a citizen of the United States of America, residing at Windber, in the county of Somerset and State of Pennsylvania, have invented certain new and useful Improvements in Rotary Engines, of which the following is a specification, reference being had therein to the accompanying drawings.

10 The invention relates to certain new and useful improvements in rotary engines; and the invention has for its object to provide a novel form of engine which is particularly adapted for use in connection with locomobiles and the like gas or steam driven vehicles.

15 The primary object of the invention is to provide an engine from which the greatest amount of power can be derived from the least expenditure of gas, and in constructing my improved engine I aim to form the same as compact as possible, whereby it will occupy a comparatively small space in a locomobile or the like vehicle.

20 Another object of this invention is to provide a rotary engine which will be extremely simple in construction, strong and durable, comparatively inexpensive to manufacture, and highly efficient for the various purposes 25 for which it may be used.

With the above and other objects in view the invention consists in the novel construction, combination, and arrangement of parts to be hereinafter more fully described and 30 then specifically pointed out in the claims, and, referring to the drawings accompanying this application, like numerals of reference designate corresponding parts throughout the several views, in which—

35 Figure 1 is a side elevation of my improved engine. Fig. 2 is a vertical sectional view. Fig. 3 is an end view. Fig. 4 is a bottom plan of one part of the housing of the engine. Fig. 5 is a diagrammatic view illustrating a 40 plurality of my improved engines arranged to operate in unison to drive a common shaft. Fig. 6 is a detail sectional view of one of the packing-rings of my improved engine.

45 To put my invention into practice, I construct my improved engine of a bed-plate 1, having upwardly-extending side frames 2 2. The side frames of the bed-plate are cut away, forming windows 3 3, and the tops of the side frames are countersunk, as at 4, and provided with diametrically opposite journal-

5 boxes 5 5. The bed-plate 1 is provided with a central opening 6, and the sides of the bed-plate are pierced, as at 7, to permit of bolts 8 passing therethrough in order that the bed-plate may be secured to a suitable foundation.

Revolutely mounted in the journal-boxes 5 5 between the side frames 2 2 is a shaft 9, upon which is mounted a wheel 10. The periphery of the wheel is provided with a 60 tangentially-disposed pocket 11, the object of which will be presently described. Fitting upon the side frames 2 2 and inclosing the upper half of the wheel 10 is a housing 12, said housing being secured to said frames, as 65 at 14 14. The housing, which is semicylindrical in form, has its inner curved sides provided with packing-rings 15 and 16, the packing-ring 15 being arranged in suitable form to surround the tangentially-disposed inlet-port 17, formed in the housing 12, while the packing-ring 16 is arranged to surround a radially-disposed outlet or exhaust port 18, formed in the housing 12. Each one of the 70 packing-rings comprises a plurality of casings 19, which are arranged within the grooves 19^a, surrounding the ports 17 and 18. The casings 19 are substantially channel-shaped, and interposed between the casings and the bottom of the grooves 19^a are curved 75 band-springs 20, which normally hold the casings in engagement with the periphery of the wheel 10.

In each casing is mounted a bearing-strip 21, said strips being held in engagement with 80 the wheel 10 by spring 22, mounted in the casings 19, said springs being similar to the springs 20 heretofore mentioned. The double-ended packing-rings are adapted to form an air-tight connection with the periphery 85 of the wheel 10 around the inlet and exhaust ports 17 and 18. The inlet-port 17 is adapted to connect with a suitable supply of gas, while the outlet-port 18 may exhaust at any convenient place.

100 In the central opening 6 of the bed-plate 1 I place a lubricant-receptacle 23, said receptacle being secured to the side frames 2 2 of the bed-plate, as at 24. In the receptacle 25 oil or the like lubricant is placed, and the 105 periphery of the wheel 10 is adapted to pass through the oil or lubricant to assist the rotation of the wheel within the housing 12. To prevent an excess amount of lubricant 110 being carried upon the periphery of the

wheel 10, I provide the side frames 3 3 with two transversely-arranged strips 25 25, and between these strips is mounted a piece of leather or the like flexible material 26, the edge of the resilient material being adapted to bear against the periphery of the wheel and remove an excess amount of lubricant that may be carried upwardly by the revolving wheel 10.

10 To further lubricate the wheel, the caps 27 of the journal-boxes 5 are provided with conventional oil-cups 28, adapted to lubricate the revolving shaft.

Upon gas or steam entering the inlet-port 17 and the pocket 11 of the wheel 10 registering with said inlet the gas or steam drives the pocket toward the exhaust-port 18, the gas or steam being retained within the pocket until the port 18 is reached, at which time 20 the gas or steam can exhaust.

In Fig. 5 of the drawings I have illustrated the manner in which I preferably arrange my improved engine in order that a continuous operation of the shaft 9 may be accomplished. It will be observed that I employ engines 29, 30, 31, and 32, the wheels 10 of said engines being mounted upon a common shaft 33. While the wheel 10 of the engine 29 is taking gas the wheel 10 of the engine 30 is exhausting, and while the wheel 10 of the engine 29 is exhausting the wheel 10 of the engine 31 is taking gas. As the wheel 10 of the engine 31 is exhausting the wheel 10 of the engine 32 is taking gas, it being observed 35 that the pockets 11 of the wheels 10 of the engines are arranged at right angles to one another, and in this manner a continuous rotation of the shaft 33 is accomplished, one engine always taking gas while another is 40 exhausting.

It is thought from the foregoing that the construction, operation, and advantages of the herein-described rotary engine will be apparent without further description, and 45 various changes in the form, proportion, and minor details of construction may be resorted to without departing from the spirit and scope of the invention or sacrificing any of the advantages thereof.

What I claim, and desire to secure by Letters Patent, is—

1. The combination of a plurality of engines, having a common shaft, each engine embodying a wheel mounted upon said shaft, and having a pocket formed therein, a housing mounted over each wheel and having inlet and exhaust ports formed therein, bearing-rings mounted in said housings and adapted to engage the peripheries of said wheels, means to lubricate said wheels, substantially as described. 55

2. The combination of a plurality of engines having a common shaft, each engine embodying a wheel having a tangentially-disposed pocket formed therein, a housing mounted over each wheel and having inlet and exhaust ports formed therein, means to establish an air-tight connection between the periphery of said wheels and said housings surrounding said ports, and means to lubricate said wheel, substantially as described. 65

3. The combination of a plurality of engines having a common shaft, adapted to be driven by said engines, said engines embodying wheels mounted upon said shaft, separate 75 housings mounted one over each of said wheels, said wheels having pockets formed therein, the pocket in one wheel being out of longitudinal alignment with the pocket in another wheel, said housings having inlet and 80 exhaust ports formed therein, substantially as described.

4. A rotary engine embodying a bed-plate and side frames, a wheel journaled in said side frames, said wheel having a pocket 85 formed therein, a housing carried by said side frames, said housing having inlet and exhaust ports formed therein, bearing-rings carried by said housing, and engaging the periphery of said wheel, and means to lubricate 90 the periphery of said wheel, substantially as described.

In testimony whereof I affix my signature in the presence of two witnesses.

CLARK J. DUNCAN.
